Attorney

UNITED STATES PATENT OFFICE.

FELIX LAWRENCE SAINO, OF MEMPHIS, TENNESSEE, ASSIGNOR TO SAINO FIRE DOOR & SHUTTER CO., OF MEMPHIS, TENNESSEE, A CORPORATION OF TENNESSEE.

FIRE DOOR OR SHUTTER.

1,146,960.

Specification of Letters Patent. Patented July 20, 1915.

Application filed January 25, 1912. Serial No. 673,291.

To all whom it may concern:

Be it known that I, FELIX L. SAINO, a citizen of the United States, residing at Memphis, in the county of Shelby and State 5 of Tennessee, have invented certain new and useful Improvements in Fire Doors or Shutters, of which the following is a specification.

My invention relates to certain new and 10 useful improvements in fire doors and shutters, and has especial reference to that class of sheet metal doors which is fully described and claimed in the prior Patent No. 982,303, January 24, 1911.

15 An essential object of the present invention is to improve the construction of the door or shutter, first, by simplifying the construction in that the stiffening frame of the door comprises fewer parts; second, by doing away with the raw edge of the front wall which is shown as lapping the vertical stiffening frame in the former patent.

20 My present invention materially cheapens the cost of the door while at the same time 25 improving its appearance. To accomplish this end I retain most of the essential features shown in the former patent, but dispense with certain parts which I deem unnecessary in doors or shutters for openings 30 of ordinary size. The slidable stiffening bar, shown as 14 Figure 7 in the prior patent is not used in my present invention as I find that by interlocking the stiffening channels of the frame with the front wall of the 35 door, these stiffening channels are held in sufficiently rigid alinement in doors of ordinary size by the interlock. The spacing bar shown as 11 Fig. 7 of the prior patent may also be dispensed with in doors of ordinary 40 size. In the present construction, which is hereinafter fully explained, the door or shutter is made with the front wall substantially in a single sheet of metal, and the rear wall is comprised of a plurality of 45 overlapping sheets of metal, and an interposed layer of refractory material.

The interlocking flanges or edges of the sheet which constitute the front wall of the door and the outer edges of the channel

members which form the hollow side sections or stiles of the door extend substantially the full length of the door, the construction being such that the stile is expandable in a straight line, and in unison with the body of the door in substantially 55 the manner described in the aforesaid patent.

With the above and other objects in view, my invention consists of the parts and the constructions, arrangements and combination of parts, which I will hereinafter describe and claim.

In the accompanying drawing forming part of this specification and in which similar reference characters indicate like parts in the several views; Fig. 1 is a section on 65 the line X—X of Fig. 2, of a portion of the door showing the hollow stile 14 or section at one side thereof, and showing the telescoping connection between the edges of the front wall of the door and the several channel members which form the said stile or section. Fig. 2 is a rear elevation of a part of the door.

In said drawing the door is shown as consisting fundamentally of the rear wall, 1, of 75 sheet metal, a front wall, 3, of sheet metal, and an intermediate sheet, 2, of some appropriate refractory substance such as asbestos. The construction of these parts may follow more or less closely the construction 80 and arrangements of the corresponding parts of the former patent, it being understood that the front wall may, if desired, be formed of a single sheet of metal, or two or more sheets may be used, riveted together to 85 form the equivalent of a single sheet. The rear wall is formed of two or more sheets of metal independently fastened to the front wall throughout only a portion of their edges where they abut the stiles. These rear 90 sheets may be connected with each other by loose rivets in slotted holes but I prefer to interlock them in such a way as to allow one to slide away from the other when the door is under expansion.

95 The walls of the door are preferably made of corrugated metal, and when so made, the corrugations of the front wall

preferably extend vertically and the corrugations of the rear wall extend horizontally; it will be understood, however, that the corrugations of the several sheets may take 5 some other relative position and that they may extend in any manner which will be found best suited for my purpose.

The front and rear walls of the door may be riveted together by rivets, 8 and 9, at the 10 edges of the walls substantially in the same manner as shown in the aforesaid patent. In doors of ordinary size, however, I prefer to omit the collars shown on rivets, 8, at the same time dispensing with the spacing bar 15 shown at 11. The rivets, 9, serve to secure the vertical or side edges of the front and back walls and the legs of the hollow stiffening channels, 13. These rivets 9 pass through the sections, or independent sheets 20 of the rear wall and the legs of the hollow stiffening channels, 13, at points between the sections or joints of the frame or stile of the door.

The hollow section, or stile, of the door 25 which is substantially rectangular in cross section, is formed by a series of channels, 13, which overlap each other at adjacent and freely sliding ends, the channels corresponding in number substantially to the 30 number of independent sheets in the rear wall of the door. When the door is assembled the overlap in these channels coincide with the overlaps in the sheets forming the rear wall of the door. The outer legs of 35 these channels, 13, after extending to the front of the door, and parallel with the returned portion, 12 of the edge of the front wall, are turned toward the rear of the door, as at 14 until they stand parallel to 40 the returned or bent portion of the front wall, 12, the bent portions of the channels and the bent portion of the front wall fitting together in tongue and groove fashion. The telescoping parts, 12, of the front wall, 45 and the corresponding part, 14, of each of the channels, 13, are adapted to slide relative to each other when the door is exposed to high temperatures, thus providing for expansion between the edge of the front wall, 50 14, and the several sections of stiffening channels, 13.

It will be seen that by reason of the interlock of the channels, or plates, 13, with the edge of the returned portion of the 55 front wall, the bar shown at 14, Fig. 7 in the former patent may be dispensed with as the channels will be held in alinement by the interlock; and the stile will be stiffened by four thicknesses of metal at the vertical 60 edges of the door. For the same reason the spacing and stiffening bar, 11, and the collars or washers, 10, on rivets, 8, may be dispensed with, thus further cheapening the cost of the door.

Having thus described my invention what 65 I claim as new and desire to secure by Letters Patent is:—

1. In a fire door or shutter having front and rear walls of sheet metal and an intermediate sheet of refractory material, a rear 70 channel member having one edge fixed to said walls and intermediate sheet and having the remaining portion bent to form a hollow stile section which is substantially square in cross section, said front sheet extending across the edge of the door and thence bent and returned toward the front, and said channel member having a terminal portion which is bent toward the rear of the door and foldably interlocked in sliding 75 relation to the returned portion of front sheet whereby the sheet and channel members are expansively connected.

2. In a fire door or shutter having a front wall substantially in a single piece and a rear wall comprised of a plurality of overlapping metal sheets free to slide at their overlaps and attached to the front wall independently of each other, a vertical stiffening frame composed of a plurality of stiffening sections, the number of said sections corresponding with the number of sections comprising the rear wall of the door, said stiffening sections having their outer edges foldably connected to the vertical edges of 80 said front wall to form a slidable interlock 85 which compensates for unequal expansion.

3. In a sheet metal door, or shutter, having front and back walls, stiles formed in part by a plurality of overlapping stiffening means each attached to said walls independently of each other at points between their overlapping ends, said stiffening members being held in alinement by their fastenings to said walls, and by an interengaging 90 folded tongue and groove connection with the edge portion of the front wall.

4. In a sheet metal fire door or shutter having front and back walls, a plurality of stiffening members attached to the main 100 part of the door, and a stiffening frame formed in part by the overlapping of the front wall and in part by the stiffening members, said stiffening members being substantially square in cross section and having 105 edge portions foldably interlocking with the edge portion of said front wall.

5. In a fire door or shutter having a front wall substantially in a single piece of metal, a rear wall composed of a plurality of overlapping independent metal sheets, and an interposed layer of refractory material, a 110 stiffening frame comprising a plurality of overlapping stiffening members, the number of said members corresponding substantially 115 with the number of metal sheets in the rear wall of the door, said stiffening members being held in alinement by rivets, by 120

125

their overlapping and telescoping ends, and by foldably connecting the edges of the stiffening members with the edges of the front wall of the door or shutter, whereby the stiffening frame expands in unison with the door or shutter when the same is exposed to high temperatures.

6. In a sheet metal fire door or shutter structure, the combination of a stiffening frame comprising a plurality of overlapping stiffening members and independent fas-

tenings therefor, and a slideable tongue and groove interlock formed by foldably connecting the edges of the members with the edges of the door.

15 In testimony whereof I affix my signature in presence of two witnesses.

FELIX LAWRENCE SAINO.
